UNITED STATES PATENT OFFICE.

THEODORE J. RABITZER, OF DAYTON, OHIO.

DISPLAY HOLDER.

Application filed March 31, 1924. Serial No. 703,081.

My invention relates to supports of the spring clamp type, and more particularly to a spring pressure clamp co-operating with some other supporting structure, as the 5 glass of a window, show case, a wall, a piece of machinery, kegs, casks, or other articles for holding in adjusted position thereon, a display card, price tag, descriptive circular or the like, or for displaying small articles 10 of merchandise.

In the present invention there is contemplated a strip of spring material, preferably though not necessarily, spring steel, of thin flexible character, which is bent into a 15 U-shaped bight, one leg of which is longer than the other and is adapted to be thrust into any convenient crevice or recess, or to be otherwise secured to a supporting structure, upon which the short arm of the U- 20 shaped bight bears with more or less pressure due to the inherent tension of the spring strip. This shorter leg of the bight is preferably provided with a claw like head having tines or spurs for engaging the display card or article. Any attempt to withdraw the supported card, display sheet or article from beneath the claw or head tends to distort the bight of spring material increasing its pressure tension. For convenience in applying the device and to retain it 25 in condition for easy and quick application, one leg of the yielding spring bight is slid- 30 ingly engaged with the opposite leg by means of a keeper or arm, having therein a 35 slot through which the longer leg of the bight is extended.

The object of the invention is to simplify the structure as well as the means and mode of operation of yielding spring clamp supports, whereby they will not only be cheapened in construction, but will be more efficient in use, positive in operation, durable, and unlikely to get out of repair.

A further object of the invention is to 45 provide an adjustable yielding spring clamp support, the engaging tension of which will be materially increased by an attempt to withdraw the display card or supported article from beneath the support without first 50 disengaging it from the supporting structure.

A further object of the invention is to 55 provide an article of manufacture, which will securely hold display cards and small articles of merchandise and which will readily accommodate itself to varying thick-

nesses of such cards or articles, and which is readily adaptable to different conditions of use and to different structures to which it may be applied. The purpose is to provide such a spring clamp support which will be universal in its application to a wide 60 range of purposes.

With the above primary and other incidental objects in view as will more fully appear in the specification, the invention consists of the features of construction, the parts and combinations thereof, and the mode of operation or their equivalents as hereinafter described and set forth in the 70 claims.

Referring to the accompanying drawings wherein is shown the preferred, but obviously not necessarily the only form of embodiment of the invention, Fig. 1 is a perspective view of a portion of a window or a display case to which the present spring pressure clamp has been applied for supporting a show card, the device and card being viewed from the rear. Fig. 2 is a 75 perspective view illustrating the application of the device to a barrel. Fig. 3 is an enlarged detail perspective view of the spring clamp support, detached from the display card and supporting structure. Fig. 4 is a 80 plan view illustrating the normal relation of the clamp to the abutment surface and display card.

Like parts are indicated by similar characters of reference throughout the several 85 views.

In erecting window displays for advertising or other purposes, displaying show cards, price tickets, or bulletins, it is frequently desirable to attach such matter to glass fronts or show windows. Ordinarily, such matter must be pasted or glued to the window. The present form of spring clamp is designed to hold such matter pressed tightly 90 against the glass of the window, or against the glass front or top of a show case. The pressure clamp is attached by thrusting one leg of the device into any convenient crevice in the window framing or between the walls or glass front and frame of the show case, 95 beneath the hoop of a barrel or cask, or beneath any convenient part or into any crack or crevice of the piece of machinery. The pressure clamp support consists of a length 1, of flexible spring material similar 100 in character to commercial clock spring steel, which may be used for clamp supports of 105 110

2
smaller size, but for those of larger size a spring steel of somewhat greater thickness or increased tension is to be preferred. The length of spring material is bent upon itself 5 to form a substantially U-shaped bight 2, one leg 3 of which is somewhat longer than the opposite leg 4. The short side of the bight 2 is slidably engaged with its longer leg 3 to form a noose, thus placing the strip 10 of material under tension. The side of the noose exerts lateral pressure against the abutment surface with which the device is engaged. The noose thus formed, carries a plurality of article engaging spur teeth 6 15 which may be either integral with the strip or attached thereto. The short leg 4 in the particular embodiment illustrated is formed at its extremity into a head or claw 5, preferably though not necessarily provided with 20 a number of small spurs or sharpened teeth 6, which engage a show card or other article to be supported and hold the same against slippage. The shorter leg 4 of the bight 2 is reduced somewhat in width as it approaches 25 the head or claw 5, as is indicated at 7. Such reduction of the width of the strip is not essential. It is, however, a matter of convenience and improves the appearance of the device, makes it less bulky and distributes the tension or yielding resistance of 30 the clamp support in a more desirable manner. The extended leg 3 of the clamp support is preferably sharpened somewhat at its extremity to facilitate its introduction 35 into the rabbet of a window frame beside the glass, beneath a barrel hoop or into any other opening or beneath any overhanging support or ledge.

To retain the clamp in its U-shaped form 40 and in condition for instant application to a display card or article of merchandise, the short leg 4 of the bight is provided with an arm or keeper 8, having therein a slot 9, through which the longer leg 3 of the support projects. To facilitate the sliding adjustment of the keeper or arm 8 upon the longer leg 3 of the device, the bearing side 45 of the slot 9 is of arcuate form, whereby it is afforded only a limited bearing along a central line of the leg or strip.

In use the longer leg 3 of the clamp support is thrust into a convenient crevice as in the rabbet of the window frame beside the glass or beneath the hoop of the barrel. This 50 leg is thrust in such crevice in such relation that the claw or head 5 of the device is turned toward and exerts its pressure in the direction of the window glass, show case front or top, or the side of the barrel, as the case may be. The display card or article to be supported is interposed between the head or claw 5 and the glass of the window or show case. It is securely held in its supported position by the spring tension of the 55 clamp. However, upon any attempt to with-

draw the card without first withdrawing the support itself will tend to flex or distort the bight 2 by drawing the head or claw 5 toward the bottom of the bight with the movement of the card, with which it has positive engagement by means of its teeth or spurs. This distortion of the bight 2 materially increases the spring tension of the clamp upon the display card or article held, thereby increasing the resistance to the withdrawal of the supported article. 75

It is to be understood that the device may be made in various sizes to meet different conditions of use and may be made of material possessing greater or less strength and tension, according to the character and size of the display card or articles of merchandise to be supported. It is to be understood that the article is of general application and that the instances of use before mentioned are for illustrative purposes only, and not with any intent of prescribing the use and application of the device. 80

From the above description it will be apparent that there is thus provided a device of the character described possessing the particular features of advantages before enumerated as desirable, but which obviously is susceptible of modification in its form, proportions, detail construction and arrangement of parts without departing from the principle involved or sacrificing any of its advantages. 85

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is therefore, claimed in any of its forms or modifications within the legitimate and valid scope of the appended claims. 105

Having thus described my invention, I claim:

1. As an article of manufacture, a clamp support, comprising a length of flexible spring material bent upon itself into a U-shaped bight having legs of unequal length, outwardly directed anti-slip spurs at the extremity of the shorter leg, and a slotted extension upon the shorter leg through which the longer leg slidably extends. 115

2. As an article of manufacture, a supporting member comprising a slip noose of spring material, the standing portion of which is for engagement relative to an abutment surface against which the side of the noose exerts spring pressure incident to the inherent resiliency of the material, and article engaging spurs formed integral with said strip. 125

3. As an article of manufacture, a strip 130

of spring material bent upon itself into a bight, one end of said bight having sliding engagement with a mid-length portion of the strip forming the opposite side of the bight to form a noose, and article engaging spurs carried by the noose.

4. As an article of manufacture, a length of spring material bent upon itself into loop formation with one end of the strip being 10 slidingly engaged with the strip near the other end thereof, the last mentioned end beyond such sliding engagement being adapted to be thrust into a crevice in approximate relation to an abutment surface 15 against which the loop exerts a lateral pressure under the inherent tension of the material to clamp therebetween an interposed article.

5. As an article of manufacture, a length 20 of spring material having at one end thereof, an eye through which the other end of the strip may be slidingly thrust, and spur teeth carried by said spring strip.

6. A pressure clamp support coacting with 25 an abutment surface, including a U-shaped spring bight, one end of which is engageable in fixed relation with the abutment surface against which the other end of the spring bight exerts expanding pressure, to hold an 30 interposed article, and a keeper member carried by one side of the bight and slidingly engaging the other side of the bight and limiting its flexing movement.

7. A pressure clamp support coacting 35 with an abutment surface including a U-shaped spring bight, one end of which is engageable in fixed relation with the abut-

ment surface, against which the other end of the spring bight exerts expanding pressure, to hold an interposed article, a slotted 40 arm carried by one side of the bight through the slot of which the other side of the bight is slidingly adjustable.

8. A pressure clamp support coacting with an abutment surface including a U- 45 shaped spring bight, one end of which is engageable in fixed relation with the abutment surface against which the other end of the spring bight exerts expanding pressure to hold an interposed article, and a 50 keeper carried by one side of the bight having an arcuate bearing surface upon which the other side of the bight is slidingly adjustable to vary the size and with it the tension of the bight. 55

9. As an article of manufacture, a clamp support comprising a slip noose of spring material, the standing part of which is engageable in proximate relation with an abutment surface, against which the running portion of a noose exerts lateral pressure by the inherent tension of the material to clamp a supported article between the noose and the abutment surface. 60

10. As an article of manufacture, a clamp 65 support for cooperation with a proximate abutment surface, comprising a strip of spring material formed into a running noose, and anti-slip spurs carried by the running portion of the noose. 70

In testimony whereof, I have hereunto set my hand this 28th day of March A. D. 1924.

THEODORE J. RABITZER.
